William F. Nickel.

UNITED STATES PATENT OFFICE.

WILBUR C. POTTER, OF NEW BRUNSWICK, NEW JERSEY.

THREAD-GUIDE.

1,326,371.

Specification of Letters Patent. Patented Dec. 30, 1919.

Application filed November 16, 1917. Serial No. 202,276.

To all whom it may concern:

Be it known that I, WILBUR C. POTTER, a citizen of the United States, residing in New Brunswick, in the county of Middlesex and 5 State of New Jersey, have invented certain new and useful Improvements in Thread-Guides, of which the following is a specification.

I have invented an improvement in thread 10 guides, particularly thread guides to be used upon the so-called stop-motion mechanisms of knitting and other textile producing machines.

The primary object of my invention is to 15 provide a thread guide which is of such shape that it will always direct the thread into engagement with the trip lever of the stop motion mechanism; and which can be used with or without a guard for the thread 20 on its way to the trip lever, as the operator desires.

Other objects and advantages will appear from the following description taken in connection with the accompanying drawings; 25 and the novel features of my invention will be precisely defined in the appended claims. This disclosure, however, is explanatory only, and I may employ embodiments other than what is actually shown herein to the 30 full extent indicated by the general meanings of the terms in which the claims are expressed.

On the drawings:

Figure 1 is a side view showing my im- 35 proved thread guide mounted in position on its support, which is the arm of a stop motion mechanism;

Fig. 2 is an end view of such an arm with the guide thereon;

Fig. 3 is a view of a blank from which 40 my improved guide is made; and

Fig. 4 is a detail view showing the relative positions of the end of the trip lever and that portion of the guide adjacent the same 45 when the thread is passing the trip lever.

The same numerals of reference identify the same parts throughout.

In the particular description of the structure shown in the drawings, the numeral 1 50 indicates an arm which is mounted on and projects from a casing inclosing the parts of a stop-motion mechanism; but as both the casing and the mechanism it contains are well known and not a part of my invention, it is not necessary to show them on the drawings or describe them herein. The 55

guide made in accordance with my invention is indicated at 2, and is mounted at the outer end of this arm by securing it above and below to a head 3. On the arm 1 and below the same near the head 3 is pivoted the trip lever 4, which has the form of a bellcrank, and projects at one extremity into proximity to the portion of the guide which is farthest from the arm 1. I also may employ a guard 5 for the thread in combination with the guide 2; this guard when present being secured to the lower end of the head 3 projecting away from the arm in the same direction as the guide so as to co-operate with the same and with the lever 4. 60 65 70

Preferably the guide 2 is made by stamping a blank out of a sheet of metal or some other substance, giving it the form shown in Fig. 3. The blank may accordingly be 75 yoke-shaped; comprising a pair of arms 6, terminating in laterally extending ears 7; which are adapted to be bent over toward the same face of the blank and perforated to enable them to be secured to the top and bottom of the head 3 by means of screws. The shank of the yoke is not straight, but is turned to one side of the long axis of the blank, as shown in Fig. 3; so that when the blank is finally shaped to make the guide, 80 85 90 95 100 105 110

and when the guide is mounted upon the head 3, the guide will terminate at its outer end in a tail 8; and the edge of the blank from the extremity of this tail to the ear 7, which is to be made fast to the top of the head 3, will be curved so that when the guide is mounted on the arm 1, a thread placed upon the upper part of this curved edge, which is indicated at 9 in the drawings, near the head 3, will slide down along this edge until it is stopped by the outer end of the lever 4. I of course polish this curved edge 9, so as to round the corners of the same and remove all burs and jagged projections; and make the same as smooth as is possible. When finished the guide 2 will be concave on the face to be presented to the lever 4, and convex on its opposite face.

The lever 4 is mounted upon a suitable pivot post 10 which projects downward from the lower face of the arm 1, and terminates in its forward end adjacent the tail 8 in a portion for engaging a thread; such as a fork having prongs or points 11, and at its opposite end it carries a hook 12. The prongs 11 do not come into contact with the guide 2; and when this lever is moved so

as to carry the points or prongs 11 as close to the guide 2 as they will go, the plane of the prongs will be approximately parallel to the plane of that portion of the guide which 5 is adjacent the tail 8; as indicated in Fig. 4. The forward prong 11 of the lever 4 is longer than the other prong. The latter will not extend as far as the edge 9 of the guide 2, but will terminate short of that edge; while 10 the forward prong 11 which is longer, will extend beyond this edge so that when a thread is placed on the guide near the head 3 it will be arrested by the lever 4 as soon as it slides down along the edge 9 sufficiently 15 far to engage the forward prong 11. The thread will then be held by the lever and run between the points 11 of the fork as it passes toward the stop-motion on its way to the knitting needles. This thread is indicated 20 by the broken lines in Fig. 1, at 13.

In practice the lever 4 is so related to the stop-motion mechanism that it is yieldably held in the position indicated in Figs. 1 and 2. So long as the thread runs smoothly 25 over the fork and past the other parts of the stop-motion mechanism, not shown, which are to be controlled by the thread, the operation of the knitting machine will continue. If, however, the thread or yarn should be 30 come tangled by getting bunched or knotted, the knot will actuate the parts of the stop-motion mechanism controlled by the thread as the knot or bunch passes same, allowing the stop-motion mechanism to come into 35 play and stop the knitting machine before any damage to the thread can occur. When this interruption occurs, the element, not shown, which engages the hook 12 of the lever 4 releases this lever; allowing it to 40 swing away from the guide 2; and the thread to drop out from between the prongs 11. The attendant then gives the knitting machine proper attention, removing or 45 smoothing out the knot or bunch in the yarn and making ready for further operation. After the knot or bunch is removed the parts of the stop-motion mechanism are returned to their former positions and the lever 4 allowed to swing back until the 50 points 11 are again in proximity to the lower part of the guide 2. The thread is then laid upon the upper part of the guide so that it can slip down along the curved edge 9 into the fork, and the knitting machine can thus be started over.

The guard 5, which may be included, consists of a piece of metal which is turned down at its front end and twisted slightly as indicated in Figs. 1 and 2, so that the 60 edge indicated at the right in Fig. 1 can engage the thread as it passes to the lever 4. The friction of the thread running in contact with this edge, which is of course made smooth by polishing, is sufficient to straighten 65 out any loops or tangles and thus prevent

the thread from becoming knotted to such an extent that it would work the stop-motion mechanism and stop the knitting machine. This guard may be included or not, according to the nature of the work to be 70 performed, and the preference of the operator.

My invention, of course, is not confined to a guide having the exact shape shown in Figs. 1 and 3. For example, instead of the 75 two arms 6, this guide may be made of a continuous sheet of metal without any recess cut into it separating the arms 6. Neither is it necessary for me to utilize a lever having the exact shape of the lever 4, 80 as under many circumstances a trip lever which is not provided with a fork at its outer end may be utilized instead. My invention relates principally to the guide and the manner of mounting the same so that 85 the thread can be directed easily into the space between the points 11 of the lever 4. And I wish to call attention to the fact that the guide and the lever are so mounted with respect to each other that the space between 90 the prongs and the lever 4 is never obstructed by the guide, but remains open at all times because the guide is so curved that it extends not only outward from the one end of the arm 1, and from above to below 95 the latter, but also toward the opposite end of the arm 1; the tail 8 being bent under the fork so that the thread can slip very easily between the prongs 11 and easily out of the prongs after the lever 4 swings to 100 the right far enough to clear the tail 8 when the stop-motion mechanism causes the knitting machine to cease running.

The body of the guide 2 having the arms 6 at one end, is provided with a tail 8 at the 105 other end to extend the body; and make the edge 9 long enough to reach from the head 3 beyond the fork 4.

A projection or web 14 on the bottom of the arm 1 prevents the lever 4 moving farther to the left than the position it occupies in Fig. 1, by engaging the elbow or angle 110 of the lever 4.

The body of the guard or guide above described is adapted for use in connection with 115 stop mechanism for knitting machines of the kind disclosed in the patent to F. Crawford, 510839, granted December 12, 1893.

Having described my invention, what I claim to be new and desire to secure and protect by Letters Patent of the United States is as follows:

1. The combination of a support having a lever terminating in a fork pivoted thereon and a guide secured to the support and extending toward the fork carried by said lever, the guide adjacent said fork being substantially parallel to the plane of the prongs thereon, one prong of the fork projecting beyond the guide.

2. The combination of a support, a guide composed of a body having a pair of arms adjacent one end to enable the guide to be fixed to the support, and having a tail at the 5 opposite end of the body to extend the guide, said arms and said tail being bent to make the guide concave on one face and convex on the other, and a lever pivoted on the body adjacent the concave face of the guide.

10 3. In a device of the kind described the combination of a support having a lever pivoted thereon, said lever terminating in a fork, and a guide mounted on the support adjacent the fork, said guide having a portion 15 which is approximately parallel to the plane of the prongs of the fork and extends in proximity to said prongs and transversely thereof, without obstructing the space between said prongs, one prong of 20 the lever projecting beyond the guide.

4. The combination of a support, a lever pivoted to said support, said lever terminat-

ing in a fork, a guide mounted on the end of the support adjacent the lever, said guide having an edge which is curved to extend 25 downward from above the support to a point below the same and toward the opposite end of the support, one prong of the lever projecting beyond said edge, and a guard fixed to the support below the guide, 30 said guard having a downward turned end.

5. The combination of a support, a guide comprising a body having one end shaped to enable it to be fixed to the support and having a tail at the opposite end of the body 35 to extend the same, said guide being concave on one face and convex on the other, and a lever pivoted on the support adjacent the concave face of the guide.

In testimony whereof, I have signed my 40 name to this specification this 9th day of November, 1917.

WILBUR C. POTTER.
